UNITED STATES PATENT OFFICE.

SAMUEL STUCKEY, OF NIAGARA FALLS, ONTARIO, CANADA.

PHOTO EASEL.

Application filed September 23, 1924. Serial No. 739,345.

To all whom it may concern:

Be it known that I, SAMUEL STUCKEY, a subject of the King of England, residing at Niagara Falls, Province of Ontario, and 5 Dominion of Canada, have invented certain new and useful Improvements in a Photo Easel, of which the following is a specification.

This invention relates to an improved 10 easel and it has more particular reference to a device of this class which has been especially designed for displaying and supporting photographs.

In accordance with my conception, I have 15 evolved an easel which, in general appearance, represents a bound book or volume.

Broadly the improved device comprises a 20 book simulation embodying two separate frames mounted on backing pieces bound together in book fashion, the frames being 25 hinged together so that two halves are provided which are capable of being swung into the same horizontal plane when the book is laid flat, or which are capable of being disposed in forwardly diverging relation when 30 the book is stood on its end to serve as an easel.

One feature of the invention is to provide 35 frames which are artistic to render the article attractive and which have their peripheral edges shaped to simulate the pages of a book when halves are swung together.

Other features and advantages will become apparent from the following description 40 and drawing.

In the accompanying drawing forming a part of this application and in which like numerals are employed to designate like parts throughout the same:

40 Figure 1 is a perspective view of a book easel constructed in accordance with the present invention.

Figure 2 is a plan view with the halves 45 swung open and into a plane with each other.

Figure 3 is a transverse central section of Figure 2.

In the drawing, the reference characters 1 and 2 designate backing pieces which may be of light weight wood, paper board or 50 suitable material. In the completed device, these parts represent the book covers. To further this aim, the opposed inner edges of the backing pieces are partially attached together by a leather binder 3. Secured to the inner face of the backing member 1 is 55 an oblong frame 4 composed of appropriate

material, the same occupying a space such as will permit the marginal edges of the backing beam 1 to project beyond the same in the manner shown in the drawing. In practice, this frame may well be made of molding and it may be provided with an endless groove 5 to give the appearance of inner and outer frames (see Figure 2). Fitted into the frame is a card board picture or the like 60. The picture may well have an ovate photo containing area 7 as seen in Figure 2. The frame 4 is connected by hinges 8 to a retaining frame 9 secured to the inner face of the other backing piece 2. Removably fitted into the retaining frame 9 is a suitably designed picture frame 10 including a photograph 11 and a protective glass cover 12.

It is to be observed from Figure 3 that the 65 retaining frame 9 has one of its side pieces provided with a recess 13 to accommodate the head of a retaining latch 14. The retaining latch may be pressed by a spring 15 to render it effective and it may be released 70 by the finger piece 16 with which it is equipped. Although it is not essential, I might direct attention to the fact that the removable picture frame 10 may well accommodate a plurality of separate and small 75 pictures as indicated in Figure 2. I might also direct attention to the fact that the vertical edges of the frames as shown in Figure 1 may be shaped to simulate the pages of a book to provide a more accurate representation.

It has been before said that the device 80 serves as an easel, and it is obvious that by swinging the halves of the book representation to forwardly divergent relation and resting the device on one end, the result sought will be accomplished and the pictures or photos will be displayed. Devices of this 85 class when not in use will simulate a book as stated and will well serve to occupy vacant spaces in library cases, cabinets and the like. Such articles may be manufactured and sold at a price considerably less than books of equivalent sizes. Thus, a cabinet may be 90 filled with artificial books at a comparatively low cost.

Having thus described the invention, what I claim is:

As a new article of manufacture, a photo 95 easel comprising a pair of substantially rectangular frames, the marginal edges of the side pieces of which are constructed to rep-

resent a plurality of book-leaves, a backing member secured to and covering the outer face of each frame, the outer and end edges of said backing members extending outwardly beyond the corresponding edges of the side pieces of the frame to permit said backing members to coact in forming the representation of the covers of a book, the inner opposed edges of said backing members terminating flush with the adjacent side pieces of the frame and forming a space between said frame when the frames are

swung open into the same horizontal plane, hinges positively connecting said frames and backing members together, and a flexible binder attached to the opposed longitudinal edges of the backing members to complete the book simulation, the central portion of the binder being foldable into and between the leaves of the hinges when the book is open. ¹⁵ ²⁰

In testimony whereof I affix my signature.

SAMUEL STUCKEY.
